RETRACTABLE LANDING GEAR FOR
AIRCRAFT

Jean Mercier, Neuilly-sur-Seine, France

Application December 11, 1937, Serial No. 179,246
In France September 27, 1937

3 Claims. (Cl. 244—102)

The known landing gear usually comprises a landing device connected to the wheel, and a jointed strut which provides for the locking in the unfolded position. The lifting is effected by a jack which is generally mounted between the jointed strut and the airplane, or upon the said strut. Such devices have a lifting couple which provides an excess of power when the device is unfolded.

10 The present invention, has for its object to overcome this drawback, and it relates to landing gear of the disappearing type for airplanes or the like, it being chiefly characterized by the fact that it comprises a jack or similar lifting device which operates principally between the landing gear to be folded up, and the airplane, and is so arranged as to exercise, at the start of the lifting, a slight reaction upon the jointed strut, so that it will be directly bent at the time when 20 the lifting commences, and this latter may then continue, and will take place chiefly by the direct effort exerted by the jack or the like. In this manner the bending of the strut in the middle is commenced, thus avoiding the use of a 25 very great force which would be otherwise required for the lifting.

According to another characteristic of the invention, the jack is pivoted at one end to the jointed strut either directly or indirectly, in the 30 immediate vicinity of one of its ends, and at the other end, directly to the device, the landing gear or the airplane body, to which latter the other end of the jointed strut is attached.

In the accompanying drawing, which is given 35 solely by way of example:

Fig. 1 is an elevational diagrammatic front view of a landing device adapted for disappearing in the lateral direction, improved in conformity with the invention.

40 Fig. 2 is a side elevational diagrammatic view of an analogous device adapted for disappearing in the longitudinal direction.

In the embodiment shown in Fig. 1, the landing gear 7 can be made to disappear by pivoting it about a longitudinal axle 9. A jointed strut 1, 1a is pivoted at 3 to the aeroplane, and at 2 to the landing gear 7. A jack 4 or like device is provided between the strut 1, 2 and the landing gear 7 and controls the displacements of this latter. One end of the jack 4 is pivoted at 5 to the element 1a of said strut, the pivot being situated quite near the point 3, upon a relatively small appendage of the strut extending beyond this point and on the side next the airplane body.

The other end of the jack is pivoted at 6 directly to the landing gear 7.

The operation is as follows:

At the start of the lifting action, the jack 4 commences the folding of the jointed device by 5 the reaction exercised at 5 upon the strut 1, 1a. The jack then acts upon the head of the landing gear 7, at 6, in order to fold up the device. The said strut, which serves to hold the landing gear in the unfolded position, is thus somewhat displaced by the force which causes it to pivot about the point 3, but this force need not be considerable.

In the embodiment shown in Fig. 2, the landing gear can be folded up by pivoting about a 15 transverse axle 9. The jointed strut 1, 1a is pivoted at 2 to the landing gear 7, and at 3 to the airplane body. The end 6 of the jack 4 is connected to the airplane body, and the end 8 acts upon the landing gear 7 at 7a; also reacting upon the strut 1, 1a at 5.

The operation is as follows:

At the start of the lifting action, the jack 4 commences the folding of the strut 1, 1a, and hence the release of the landing gear, by its action at 5, and it then exerts its principal effort upon the landing gear for disappearing purposes.

Obviously, the said invention is not limited to the embodiments herein described and represented, which are given solely by way of example.

Thus the examples of construction which have been selected, are applicable to landing gear for aircraft, but it is evident that without departing from the limits of the invention, the principle herein disclosed may be applied to any 35 pivoted device which is to be moved with reference to another device having the fixed position. In like manner, the operating jack may be of the mechanical, hydraulic, pneumatic, electric or other type.

Having now described my invention, what I claim as new and desire to secure by Letters Patent, is:

1. A jointed mechanism adapted for use in a landing gear or the like comprising a control 45 means such as a jack, a folding strut, consisting of two pivoted parts, a movable member, another member having a relatively stationary position with respect to said movable member, a pivotal attachment between said two members, 50 said strut being attached at either of its ends to one of said two members, and said control means being attached at one end to said strut, and at the other end to said stationary member in the immediate neighbourhood of the pivotal 55

attachment between said movable and stationary members, the pivotal attachment between said strut and said control means being located in the immediate neighbourhood of one end of said strut.

2. A mechanism for use in a landing gear or the like, according to claim 1, and further comprising an operating connection between said control means and movable member.

3. A mechanism for use in a landing gear or the like, according to claim 1, and in which said pivotal attachment between said strut and control means is located between the ends of the strut.

JEAN MERCIER.
